SEWING MACHINE

Park A. Herr, Hillside, N. J., assignor to The
Singer Manufacturing Company, Elizabeth,
N. J., a corporation of New Jersey

Application December 13, 1941, Serial No. 422,847

5 Claims. (CL. 112—256)

This invention relates to sewing machines and more particularly to an improvement in the lubrication system employed in the sewing machine.

Since the advent of high speed operation of sewing machines, of the order of 3,000 to 5,000 stitches per minute, there has been a decided trend toward completely lubricated sewing machines, employing the splash system or various modifications thereof for automatically supplying the necessary bearing points with sufficient oil to prevent excessive wear. In those machines in which the machine-frame provides a closed lubrication compartment in the walls of which is journaled one or more circularly moving shafts, trouble has been experienced with excess oil creeping along the shafts and through the shaft-bearings to a point externally of the machine-frame where the oil is thrown off centrifugally from a member mounted on the shaft to rotate therewith, such for example as the usual balance-wheel or driving pulley. The oil thus thrown off soils the clothing and the like worn by the operative and also collects on the top of the table which supports the sewing machine, thereby rendering it difficult to handle the work to avoid contamination thereof by the oil.

The principal object of the present invention is to provide an effective seal which will prevent the escape of lubricant from a lubricant compartment in a sewing machine through the shaft-bearing during rotation of the shaft.

Another object of the present invention is the provision of an oil retaining means which is simple, cheap, compact and automatically operable during the operation of the sewing machine.

With the above and other objects in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

In the accompanying drawing

Fig. 1 is a rear elevational view, partly in section, illustrating a so-called cup-feed sewing machine, of the type forming the subject of the U. S. patent to H. Hacklander, No. 2,277,971, issued March 31, 1942, embodying the invention.

Fig. 2 is an elevational view, partly in section, of the belt-driven balance-wheel mounted upon a shaft, showing the internal annular oil-collecting groove formed in the hub and the plu-

rality of radial ducts for dispersing oil collected in the annular groove.

Fig. 3 is an elevational view, partly in section, of one of the bearing bushings in which the sewing machine main-shaft is journaled.

Referring more in detail to the drawing, the present illustrated embodiment of the invention is shown incorporated in a sewing machine comprising a machine-frame 1 having a standard 2 terminating at its upper end in a bracket 3. Formed within the standard 2 is a splash-lubrication compartment 4 closed at the base of the standard by means of a gasket 5 and a bottom cover-plate 6 suitably attached to the standard by screws (not shown).

Disposed in the splash-lubrication compartment 4 transversely of the machine-frame 1 is a main-shaft 7 journaled at its opposite ends in flanged bushings 8, 9 fixed by means of screws 10 in bosses 11, 12 preferably cast integral with the side walls of the standard 2. Mounted upon and formed in the main-shaft 7 are two eccentrics 13 and 14 and a crank 15, respectively, all of which are operatively connected by suitable trains of mechanism, as clearly disclosed in the above mentioned Hacklander application, to the stitch-forming devices and work-feeding means. Fixed on the exposed ends of the main-shaft 7 are the balance-wheels 16, 17 each having a belt-groove 18 formed in its periphery.

Considering now the construction of balance-wheel 16, balance-wheel 17 being identical with balance-wheel 16, it will be observed in Fig. 1 that the balance-wheel 16 comprises a body-portion having projecting from its inner face an extension or hub 19 formed with a raised annular rib 20 providing an oil-sling. Formed in the shaft-contacting surface 21 of the shaft-bore in the hub 19 of the balance-wheel is an internal annular oil-collecting groove 22 connected by a plurality (preferably four) of equally spaced radial ducts 23 with the surface of the annular oil-sling 20. The inner end of the balance-wheel hub 19, including the annular oil-sling 20, projects into and is surrounded by an internal annular oil-collecting cavity 24 formed in the outer end of the bearing bushing 8. The oil-collecting cavity 24 at its bottom is connected by an inclined drainage port 25 to the closed-lubrication compartment 4 within the standard 2. Formed on the periphery of the balance-wheel 16 is a lateral flange 26 which overlies the outer end of the bearing bushing 16 and is telescoped within the lateral flange 27 formed on the guard-member 28 secured between the outer

55

end of the bearing bushing 8 and the boss 11 of the standard wall.

During the operation of the machine the mechanism within the splash-lubrication compartment contacts the oil contained therein (see level indicated by L in Fig. 1) and splashes the oil about the closed lubrication compartment 4. Oil is deposited upon the oil-directing plate 29 secured, as at 30, to the machine-frame, which plate delivers the oil into suitable oil-holes 31 provided in the bearing bushings 8 and 9. The oil-hole 31 delivers the oil thus collected to the periphery of the shaft 7, thereby lubricating the shaft-bearing. To evenly distribute the oil throughout the shaft-bearing and to assist in retaining the oil within the splash-lubrication compartment, the shaft 7 is formed with a spiral groove 32 cut so that during the rotation of the main-shaft 7 the spiral groove feeds the excess oil back into the splash-lubrication compartment 4.

Any oil which creeps along the shaft 7 beyond the outer end of the spiral groove 32 runs into the internal annular oil-collecting groove 22 from whence it is delivered by the radial ducts 23 into the oil-collecting cavity 24, and then through the drainage port 25 back into the compartment 4.

4. In this manner any oil which might creep beyond the end of the spiral groove 32 is effectively collected and returned to the lubrication compartment 4. If this creepage of oil were not intercepted the oil would travel along the shaft-bore of the balance-wheel and be thrown off through the set-screw hole 33 and off the outer face of the balance-wheel hub 19.

It will be understood that any oil which finds its way into the internal annular oil-collecting groove 22 in the hub 19 is delivered through the radial ducts 23 with the aid of centrifugal force created by the rotating hub 19. Thus, a partial vacuum is produced in the internal annular oil-collecting groove 22 during the operation of the machine and any oil on the shaft between the spiral groove 32 and the hub 19 of the balance-wheel is, in effect, pumped into the annular oil-collecting groove 22 and hence returned back to the splash-lubrication compartment.

While I have illustrated the present invention as applied to a combination balance-wheel and driving pulley, it is to be understood that the invention is equally applicable to any member which might be secured on the rotary shaft and positioned adjacent the wall defining the lubrication compartment.

Having thus set forth the nature of the invention what I claim herein is:

1. In a sewing machine having a frame provided with a plurality of walls defining a lubrication compartment, stitch-forming and work-feeding mechanisms, a shaft rotatably journaled in a wall of said lubrication compartment, said wall having an annular oil-collecting cavity adjacent said shaft, and a member fixed on said shaft externally of said lubrication compartment, the improvement which consists in the provision of means for preventing the escape of oil through said shaft-bearing and onto said member, comprising, an extension on said member having formed therein a shaft-bore and an internal oil-collecting groove in that end of said shaft-bore adjacent said lubrication compartment wall, said shaft-bore substantially in contact with said shaft on opposite sides of said oil-collecting groove, an oil-sling provided on the periphery of

said extension within said oil-collecting cavity, and at least one oil-delivery duct formed in said extension and connecting said internal oil-collecting groove with said oil-sling.

5. 2. In a sewing machine having a frame provided with a plurality of walls defining a lubrication compartment, stitch-forming and work-feeding mechanisms, a bearing-bushing fixed in said wall and having an internal oil-collecting cavity formed therein, a rotary shaft journaled in said bearing-bushing, and a member disposed externally of said lubrication compartment and fixed on said shaft to rotate therewith, the improvement which consists in the provision of means for preventing the escape of oil through said shaft-bearing and onto said member, comprising a hub formed on said member, said hub provided with a shaft-bore and an internal annular oil-collecting groove in said shaft-bore adjacent said bearing-bushing, said shaft-bore substantially in contact with said shaft on opposite sides of said oil-collecting groove, an oil-sling provided on the periphery of said hub within the confines of said oil-collecting cavity in said bearing-bushing, and at least one oil-delivery duct formed in said hub and connecting said internal oil-collecting groove with said oil-sling.

3. In a sewing machine having a frame provided with a plurality of walls defining a lubrication compartment, stitch-forming and work-feeding mechanisms, a bearing-bushing fixed in said wall and having an internal annular oil-collecting cavity formed therein, means for returning oil collected in said cavity to said lubrication compartment, a rotary shaft journaled in said bearing-bushing, and a member disposed externally of said lubrication compartment and fixed on said shaft to rotate therewith, the improvement which consists in the provision of

35. means for preventing the escape of oil through said shaft-bearing and onto said member, comprising, a hub formed on said member, said hub having formed therein a shaft-bore and an internal annular oil-collecting groove in said shaft-bore adjacent said bearing-bushing, said shaft-bore substantially in contact with said shaft on opposite sides of said oil-collecting groove, a raised rib provided on the periphery of said hub and disposed within the confines of said oil-collecting cavity to form an oil-sling, and at least one oil-delivery duct formed in said hub and connecting said internal oil-collecting groove with said rib.

4. An improved oil-sealing means adapted for use in a sewing machine having a frame provided with a plurality of walls defining a lubrication compartment, stitch-forming and work-feeding mechanisms, and a rotary shaft extending through one of the walls of said lubrication compartment, comprising, a bushing adapted to be mounted in a wall of said lubrication compartment and provide a bearing for said rotary shaft, said bushing having an internal annular oil-collecting cavity surrounding said shaft and a duct for draining said cavity, a member adapted to be fixed to said shaft to rotate therewith and having one of its ends extending into said oil-collecting cavity, said member having a shaft-bore and an internal annular oil-collecting groove in said shaft-bore adjacent said bushing, said shaft-bore substantially in contact with said shaft on opposite sides of said oil-collecting groove, an annular oil-sling provided on said member is register with said oil-collecting cavity, and at least

one duct in said member connecting said internal oil-collecting groove with said oil-sling.

5. An improved balance-wheel adapted for use in a sewing machine having a lubrication compartment, a bushing fixed in said lubrication compartment provided with an internal oil-collecting cavity, and a rotary shaft extending through said lubrication compartment and journaled in said bushing, comprising, a body-portion, an extension on said body-portion adapted to project into said oil-collecting cavity, said extension formed

10 with a shaft-bore and an internal annular oil-collecting groove in said shaft-bore, said shaft-bore on opposite sides of said oil-collecting groove adapted to substantially contact said shaft, an oil-sling formed on said extension and adapted to be surrounded by said oil-collecting cavity, and at least one duct in said extension connecting said internal oil-collecting groove with said oil-sling.
